(57) **CLAIM**

The ornamental design for a fishing lure, as shown and described.

DESCRIPTION

FIG. 1 is a perspective view of a fishing lure; FIG. 2 is a left side elevational view thereof; FIG. 3 is a right side elevational view thereof; FIG. 4 is a top plan view thereof; FIG. 5 is a bottom plan view thereof; FIG. 6 is a front elevational view thereof; FIG. 7 is a rear elevational view thereof; and, FIG. 8 is a perspective view of a variation of the subject lure. The portions of the fishing lure shown in broken lines are included for purposes of illustration only and form no part of the claimed design.
